UNITED STATES PATENT OFFICE.

FRIEDRICH MÜNZ, OF STUTTGART, GERMANY.

ERROR-PREVENTING TERMINAL FOR DYNAMOS.

1,372,446.

Specification of Letters Patent. Patented Mar. 22, 1921.

Application filed May 4, 1920. Serial No. 378,914.

To all whom it may concern:

Be it known that I, FRIEDRICH MÜNZ, residing at Stuttgart, Germany, have invented certain new and useful Improvements in 5 Error-Preventing Terminals for Dynamos, of which the following is a specification:

The use of accumulators in vehicles illuminated by means of an electric dynamo is unavoidable. But a lighting installation 10 that is supplied with current from a dynamo and accumulators requires skilled attendance because by wrong connections the battery and the dynamo might sustain damage or even be destroyed.

15 The invention relates to an exchangeable terminal arrangement or connecting device by which wrong connections between the poles of the battery and the dynamo are prevented, even if the connections are carried 20 out by unskilled persons.

This is accomplished by so arranging the connecting device that it is easy to remove and to reverse according to the direction of rotation of the dynamo.

25 The tapping of the current from the dynamo terminal and the conducting of the current to the place of consumption or to the charging station is preferably carried out by means of a contact pin that may be 30 inserted from either of two opposite sides into a socket mounted in the frame of the connecting device and having two concentric contact pieces, an inner piece and a concentric outer ring. The contact pin is inserted from the one or the other side of the 35 said frame according as the one or the other surface of the connecting device is turned outward or to the front. Attached to the casing of the machine is a spring 40 plug which enters the concentric outer contact ring when the connecting device is applied to the dynamo. The spring plug which serves to conduct the current from the outer contact ring to the metallic body of the 45 dynamo or to earth, does not, however, penetrate so far into this ring as to come into touch with the said inner contact piece.

By this means all possibility of connecting to a wrong pole is avoided. The mid- 50 dle contact piece inside in the concentric ring of the socket is used for connecting the dynamo to the battery so that here also all mistakes are prevented.

A constructional form of the invention is 55 shown in the drawing in which—

Figure 1 shows a dynamo having an error-

proof terminal arrangement fixed at its commutator end, and a connection between the terminal arrangement and a distributing board, and between the distributing 60 board and a battery of accumulators.

Fig. 2 shows a section through the terminal arrangement with its concentric contact socket and through the commutator of the dynamo.

65 Fig. 3 is a horizontal section through the concentric contact socket and the terminal arrangement, and

Fig. 4 is a longitudinal section through a connecting plug that fits into the socket and 70 by which the current is tapped from the dynamo and conducted to the distributing board or battery as shown in Fig. 1.

The plate 11 Fig. 3 of the commutator end of the dynamo has a protuberance or 75 spring plug which fits into the outside ring 7 of the contact socket that is embedded or fixed in the frame of the terminal arrangement or connecting device. The spring plug is electrically connected to the plate and 80 body of the dynamo. Also fixed to the plate 11 but insulated from it is a spring contact pin that is situated lower than the concentric ring 7 on a level with the metallic conductor 4, Fig. 2. The insulating material 85 8 of the connecting device has two holes similar to 15 one in either side and the aforementioned insulated contact pin passes through the one or the other of these holes according as the one or the other face of the 90 connecting device abuts against the plate 11, this depending, of course, on which end of the concentric ring 7 is slipped onto the protuberance Fig. 3 of the plate 11. Whether the terminal arrangement is 95 slipped over the protuberance and the insulated pin into the position shown in Fig. 2 or into a reversed position in which the brush 2 occupies the position now occupied by brush 1 makes no difference as far as the 100 connection between the insulated pin and the conductor 4, and between the concentric ring 7 and the protuberance is concerned.

The carbon brushes 1 and 2 conduct the current from the commutator 3 and it passes 105 through the conducting bars 4 and 5 to the two ring shaped concentric portions 6 and 7 of the contact making socket. The current conducting parts are cast or embedded in a frame of insulating material 8. An arrow 110 9 is provided on the frame which points in the direction from the one brush to the

other and in placing the terminal arrangement in position care must always be taken that the arrow points in the direction of rotation of the armature. When the terminal arrangement 8 is removed the space 10 is disclosed to view so that the direction of rotation of the armature can be seen. If the terminal arrangement 8 is fixed to the plate 11 in such a manner that the arrow 9 points in the direction of rotation of the commutator the central contact or pole 12 of the plug that is screwed into the socket 6 will always be connected to a certain pole, say the negative pole, of the dynamo and the outer or ring contact that corresponds to 7 (or 13 or earth Fig. 1) will always be positive, for a reversal of the direction of rotation will always be accompanied by a reversal of the position of the brushes 1 and 2. Now in order to maintain the same polarity in the field winding when the terminal arrangement is reversed the one end of this winding is permanently connected to the iron or body of the machine while the other end is connected through the aforementioned insulated spring pin (not shown), that is mounted on the plate 11, to the center contact of the socket. To this end a hole 15 is provided as hereinbefore mentioned in each side of the insulation 8 through which the insulated spring pin protrudes and presses against the conductor 4 that leads to the center contact 6.

I claim:

35 1. Terminal arrangement for tapping current from a dynamo, comprising terminals

projecting from the commutator end of the dynamo, a frame adapted to abut with either of two surfaces against the said commutator end, an indicator on the frame for showing the direction of rotation of the commutator, a contact sleeve extending from the one to the other of the said surfaces of the said frame and adapted to have either of its ends slipped onto a said projecting terminal, a contact in the middle of the said sleeve, brush connections arranged in the said frame and extending from the contact sleeve and the said middle contact, and channels in either side of the said frame through which a said projecting terminal enters into contact with a said brush connection.

2. Terminal arrangement for tapping current from a dynamo, comprising a terminal projecting from the dynamo, a frame adapted to abut with either of two surfaces against the dynamo, an indicator on the frame for showing the direction of rotation of the dynamo, a contact socket passing through the said frame and adapted to have either end slipped onto the said projecting terminal, a middle contact in the said socket out of the reach of the said projecting terminal, and brush connections arranged in the said frame and extending from the socket and the middle contact.

In testimony whereof I affix my signature in presence of two witnesses.

FRIEDRICH MÜNZ.
